ATTORNEYS.

9. All of the sections are substantially V-shaped in form, the sections 8 and 9 being widest at their upper ends and terminating in a reduced portion substantially pointed 5 at their lower ends. The sections 6 and 7 are similarly substantially V-shaped, but their positions are reverse, that is their lower ends present the widest portion, and their upper ends the narrowest or pointed portion. The sections 8 and 9 form an integral part of the groove section of the piston and they also form supports for the wrist pin bosses indicated at 5. The sections indicated at 6 and 7 are entirely independent of the 10 piston as they are separated from the sections 8 and 9, such separations being obtained by cutting or slotting the skirt or sleeve section along the lines indicated at 15 10, 11 and 12. Means are, however, provided for connecting the sections 6 and 7 with relation to the sections 8 and 9, and these connections are obtained by ribbing the inner side of the piston as indicated at 13, 14 and 15. In other words it might be 20 stated that the sections 6 and 7 are connected to the sections 8 and 9 by means of the ribs 13, 14 and 15. The rib 13 forms a connection between the lower adjacent ends of the sections 6, 7 and 9. The rib 15 forms a 25 connection between the opposite adjacent lower ends of the sections 6 and 7 and the section 8. The rib 14 forms a connection between the upper ends of the section 6 and the sections 8 and 9, and the rib 14^a forms a 30 connection between the upper end of the section 7 and the upper opposite ends of the sections 8 and 9. In other words the sections 6 and 7 are supported by two ribs at their lower ends and by a single rib at their upper or 35 pointed end, and the sections 8 and 9 are not only secured at their upper ends by forming an integral part with the ring section of the piston, but they are also supported at their upper ends by the ribs 14 and 14^a; the lower or pointed ends of the sections 8 and 9 being 40 supported by the lower ribs 13 and 15, respectively.

From the foregoing it can be seen that a predetermined substantially fixed position 50 is maintained between the respective sections, and that this position is maintained by a plurality of connecting ribs. It will further be seen, by referring to Figs. 3 and 4, that these ribs are arch shaped and as such form flexible connections between the sections, which permit either free expansion 55 or free contraction of the sections forming the skirt or sleeve of the piston. Hence, if expansion takes place, the ribs will compress and thereby permit a uniform diameter to be maintained. Conversely, as the piston cools, the ribs will expand and the same constant diameter will be maintained. It is due to the flexibility of the connections 60 between the respective sections that free ex-

pansion and contraction can take place, and it is for the same reason that all danger of 65 sizing and scoring of the cylinders is prevented. A piston constructed as shown is also ideal from a point of lubrication, that is 70 a considerable portion of oil is thrown by splashing from the crank case up into the pistons and as the slots 11, 10 and 12 extend completely through the walls of the sleeve or skirt, it can readily be seen that 75 the oil will leak out through these slots and as such will become evenly distributed over the cylinder walls. Similarly, excess oil will have a tendency to return to the 80 grooves and uniform and even distribution of the lubricant is therefore maintained. A piston constructed in this manner is exceedingly light and as such may be operated at high speeds. The wrist pins may 85 be secured and lubricated in any suitable manner and as such may be changed to suit various conditions. The flexibility of the sections with relation to each other permits the use of any metal, regardless of the coefficient of expansion or the temperatures 90 to which the piston is subjected, and it will similarly automatically take up wear, as a piston of this character may be fitted with a clearance not to exceed 1/1000 of an inch when first inserted. Thus, it is obvious that 95 considerable wear may take place before piston slap will be noticed even when starting cold, idling or otherwise.

While the present piston shows a skirt 100 constructed of a number of sections, it is obvious that one or more sections may be employed, for instance where the piston is 105 large and the side thrust during the power stroke is considerable, it might be advisable to only employ one section, and to place this section on the side opposite to that 110 subjected to the power thrust. Such an arrangement would be ideal under many conditions as it still permits free expansion and contraction of the sleeve, and at the same time permits ample bearing surface on that side of the piston which is subjected to the greatest thrust.

Having thus described my invention, what I claim and desire to secure by Letters 115 Patent is—

1. In a piston of the character described a head, a ring portion and a skirt portion, a substantially V-shaped segment forming a part of the skirt, and a plurality of arch shaped lugs connecting the V-shaped segment to the skirt.

2. In a piston of the character described a head, a ring portion and a skirt portion, a substantially V-shaped segment forming a part of the skirt, said V-shaped segment being so positioned as to present its pointed or upper end towards the grooved portion and its wide or base portion towards the lower end of the piston, a pair of flexible 125 130

ribs connecting the base portion of the V-shaped section to the skirt, and a single flexible rib connecting the pointed end of the V-shaped segment to the skirt.

5 3. In a piston of the character described, a head, a ring portion and a skirt portion, said skirt portion having a plurality of oblique slots formed therein dividing the

skirt into four substantially V-shaped sections, two of said sections being formed integral with the ring portion, wrist pin bosses formed integral with said sections, and flexible ribs connecting the other two sections to the integral sections which carry the wrist pin bosses. 10
